Des. 241,518
Patented Sept. 21, 1976

241,518

PACKAGING TRAY FOR PORTION CUPS

Gilbert R. Chadbourne, Oakland, Maine, assignor to
Keyes Fibre Company

Filed Sept. 16, 1974, Ser. No. 506,276

Term of patent 14 years

Int. Cl. D9—03

U.S. Cl. D9—242

Fig. 1.

Fig. 2.

Fig. 3.

FIG. 1 is a top plan view, shaded only in the upper left, of a packaging tray for portion cups showing my new design;

FIG. 2 is a side elevational view, partly in section, taken on the line 2—2 of FIG. 1; and

FIG. 3 is an end elevational view, partly in section, taken on the line 3—3 of FIG. 1.

I claim:

The ornamental design for a packaging tray for portion cups, as shown.
